UNITED STATES PATENT OFFICE.

HARRY E. KERR, OF CLEVELAND, OHIO, ASSIGNOR TO THE CLEVELAND GAS BURNER & APPLIANCE COMPANY, OF CLEVELAND, OHIO, A CORPORATION OF OHIO.

GAS BURNER.

Application filed April 29, 1928. Serial No. 105,436.

My invention relates to an improvement in gas burners, and in general my object is to provide a small burner or burner unit adapted to produce a spreading blue flame which may be used with efficiency in small heating appliances, such as coffee urns, ovens, cook stoves, gas ranges, and other heating apparatus in which a circular sheet of flanne may be advantageously applied to a superposed object.

In the accompanying drawing showing the preferred embodiment of my invention, Fig. 1 is a top view of the burner cap, and Fig. 2 a perspective view of the prong member used to support said burner cap. Fig. 3 is a bottom view of the prong member and cap assembled, and Fig. 4 is a side view thereof. Fig. 5 is a side elevation of the mixing tube for the burner affixed to a supply pipe coupling. Fig. 6 is a sectional view of the complete burner mounted upon a supply pipe.

The invention comprises a relatively small tube 2, preferably of brass, having a hexagonal enlargement 3 at its lower end in which a cross-port 4 intersects the lower end of an axial bore 5 extending the major length of the tube. The lower extremity 6 of tube 2 is screw-threaded to permit attachment to a suitable base member 7 which in the present instance is shown as screwed to a pipe coupling 8 through which gas may be supplied. A short gas orifice 9 is provided axially in the base of the tube, the diameter of which is such that a fine stream of gas is jetted under normal pressure through the tube and to a substantial distance beyond the mouth thereof. This stream of gas entrains a certain amount of air through the lateral ports 4, which entrained air is sufficient to maintain a small blue flame at the mouth of the tube when the gas pressure is reduced or turned down low compared with normal pressure operations. When the gas is turned on full and discharged through orifice 9 under normal pressure the force or velocity of the gas stream is such that a constant flame cannot be maintained opposite the mouth of the tube unless the gas is intercepted and mixed with additional air. Briefly, the gas will blow out. Having this characteristic of the gas discharge tube in mind, I provide an intercepting plate or baffle member 10 the axis of which is coincident with the axis of the tube and the

bottom of which is dished and finished smoothly. That is the bottom 11 of the plate opposite the mouth of the tube is preferably concaved and rounded and finished smoothly to merge with an upwardly curved or rounded edge 12 of the plate. This plate is also spaced a predetermined distance beyond the mouth of the tube, the spacing means in the present device comprising a skeleton frame having forked arms 13 or prongs 14 extending on diverging lines from an angular body part 15 having a central opening to permit this part to be sleeved over tube 2 in rest position upon enlargement 3. The dished element or plate 10 is a separate cast iron member preferably, which is secured to the diverging arms or prongs 14 as follows: Thus the plate is provided with notches 16 at uniformly spaced intervals radially at its edge, which notches correspond in number and position to the radial arms 14, and each arm has a curved seat 17 opposite a reduced extremity 18 adapted to occupy notches 16. Arms 14 are made of malleable metal and when the plate is seated upon the arms the extremities 18 are bent inwardly to effect clamping engagement against the rounded portion 19 of the notch in plate 10, as shown in Fig. 6, thereby locking the plate rigidly upon the arms.

In operation, the gas which is jetted through the tube strikes the center of the smooth round cavity or recess in the bottom of the plate and the gas is caused to spread radially in all directions toward the edge of the plate. Before escaping a thorough intermix of the gas is effected with air so that a blue flame will be produced annularly around the edge of the ring. When the gas is turned down and the velocity of the stream of gas is not sufficient to cause the gas to strike the plate, sufficient air is taken in at ports 4 which is mixed with the stream of gas as it issues so that a blue flame will be maintained at the mouth of the tube. The gas may be turned down, or the pressure may drop so that a mere bead of flame may be maintained at the mouth of the tube, without back-fire, and the cap or plate covers the mouth of the tube completely and protects it from drippings or overflow from a vessel exposed to the flame.

A single burner or unit has been shown in the drawing, but obviously a series of such burners may be mounted upon a suitable

head or various styles of manifolds if desired for use in portable bake ovens, doughnut stoves, etc., and the gas may be fed into either the side or bottom of the base member 5 or coupling for the burner tube.

The prong member may be made of malleable iron or bronze, while the plate may be made of automobile cylinder iron, or any other suitable metal adapted to withstand 10 high temperatures. The cap or plate is made separate from its skeleton supporting member to permit the respective parts to be made of different materials and to permit the round surface of the cavity or pocket to be 15 smoothly finished.

What I claim, is:

1. A gas burner, comprising an air and gas commingling tube of small cross section having air orifices of restricted area therein, 20 and adapted to jet under normal gas pressure a stream of gas and air a substantial

distance beyond the mouth of the tube, a forked member sleeved upon said tube having notched edges and a small circular plate detachably clamped between the notched 25 edges of said forked member, said plate being formed with a smooth centrally concave-shaped bottom encircled by a convex-shaped zone.

2. A gas burner, comprising an air and 30 gas commingling tube of small cross section and with air orifices of restricted area, a member having diverging arms extending angularly from said member beyond the mouth of said tube, notches at the free end 35 of said diverging arms and a small circular plate detachably clamped between said arms, said plate being formed with a concave central bottom portion extending into a convex-shaped zone.

In testimony whereof I affix my signature.

HARRY E. KERR.
